MECHANICAL JUMPING JACK

Samuel I. Berger, Newark, N. J.

Application February 5, 1948, Serial No. 144,308

Term of patent 3½ years

(Cl. D34—15)

To all whom it may concern:

Be it known that I, Samuel I. Berger, a citizen of the United States and a resident of Newark, in the county of Essex and State of New Jersey, have invented a new, original, and ornamental Design for a Mechanical Jumping Jack, of which the following is a specification, reference being had to the accompanying drawing, forming part thereof, and in which

Fig. 1 is a front elevational view of a mechanical jumping jack, showing my new design, and

Fig. 2 is a side elevational view thereof.

I claim:

The ornamental design for a mechanical jumping jack, substantially as shown.

SAMUEL I. BERGER.
